UNITED STATES PATENT OFFICE.

WILLIAM F. HALL, OF PROVIDENCE, RHODE ISLAND.

*COMB FOR FLAX, WOOL, &c.

SPECIFICATION forming part of Letters Patent No. 297,794, dated April 29, 1884.

Application filed December 17, 1883. (No model.)

To all whom it may concern:

Be it known that I, WILLIAM F. HALL, of the city and county of Providence, State of Rhode Island, have invented a new and useful Improvement in Combs for Flax, Wool, &c., of which the following is a specification.

My invention relates to combs which are used for combing flax, wool, &c.; and my improved comb is also applicable to the combing of horses' manes and tails, and to other similar purposes.

The object of my invention is to produce a comb of such form as to facilitate the process of molding, and also to render the same more convenient for use.

In the accompanying drawings, Figure 1 is a side elevation of my improved comb. Fig. 2 is a top view of the same. Fig. 3 is an end view of the same. Fig. 4 is a similar view, partly in section, of the comb, showing the teeth spread apart. Fig. 5 is a top view of a portion of the comb, showing a modified form of the teeth.

In the said drawings, A designates the body of the comb, and B B' the teeth. The comb and its teeth may be made of metal, celluloid, rubber, or any other preferred or suitable material, which may be cast or molded. The teeth B B' are arranged in two series, the teeth of each series being opposite the spaces between the teeth of the other series. The body A of the comb is formed with a reduced central portion, in which a hole, a, is formed, by means of which the device is suspended from any desired place, and the edge of said body is raised, as shown at a', to afford a better hold for the operator's hand.

In Fig. 4 I have shown the teeth of the comb as bent or curved oppositely at their up-

per ends. The object of so bending the teeth is to increase their penetration into the mass of material being operated upon, and to more readily separate the strands.

In Fig. 5 I have shown the comb-teeth as being of oval or elliptical form in cross-section, in which form the comb is better adapted for stable uses than where the teeth are triangular in cross-section.

The comb may be made of either metal, rubber, or celluloid, &c., as before stated. The metal comb is cast in one piece, in a three-part mold, one of such parts forming the teeth and the other two parts forming the body with its depressions. A core is used to form the aperture a of the body.

The rubber or celluloid comb may be molded in one piece; or it may be molded in two sections on the line, x x of Figs. 2 and 3, the two sections being subsequently united by cement. In either form, however, the teeth are arranged alternately.

Having thus described my invention, I claim as new and desire to secure by Letters Patent—

1. As a new article of manufacture, a comb for flax, wool, hair, &c., having its teeth arranged in two series, the teeth of each series being opposite the spaces between the teeth of the other series, substantially as and for the purposes set forth.

2. An improved comb for flax, wool, hair, &c., having its body formed with a depressed portion and a raised edge, and formed on its upper edge with two series of teeth, the teeth of one series being opposite the spaces between the teeth of the other series, substantially as described.

3. As a new article of manufacture, the comb herein described, consisting of the body A, centrally depressed, and provided with the raised edge a' and hole a, and the teeth B B', formed upon the upper edge of the body, and arranged as described.

WILLIAM F. HALL.
